UNITED STATES PATENT OFFICE.

WILLIAM GIES, JR., OF ST. MARYS, PENNSYLVANIA.

BOX-LID HOLDER.

SPECIFICATION forming part of Letters Patent No. 677,506, dated July 2, 1901.

Application filed March 22, 1901. Serial No. 52,377. (No model.)

To all whom it may concern:

Be it known that I, WILLIAM GIES, Jr., a citizen of the United States, residing at St. Marys, in the county of Elk and State of Pennsylvania, have invented a new and useful 5 Box-Lid Holder, of which the following is a specification.

The present invention relates to box-lid holders; and one of the objects thereof is to provide a simple article of this character that will hold the cover or lid of a box so that the label located on the inner face thereof will be displayed, as well as the contents of the box.

15 A further object is to construct the holder so that the lid is positively held against movement in either direction, and the stability of the device does not depend upon a frictional clamping engagement with the end walls of 20 the box.

In order to accomplish these objects, the construction set forth in the following specification and shown in the accompanying drawings is preferred, although the right to 25 slight changes and modifications within the scope of the appended claim is reserved.

In the drawings, Figure 1 is a perspective view of a portion of a cigar-box, showing the improved lid-holder applied thereto. Fig. 2 30 is an end elevation of the same, a portion of the corner of the box being broken away to more clearly illustrate the application of the invention. Fig. 3 is a perspective view of the holder detached.

35 Similar numerals of reference designate similar parts throughout the several figures of the drawings.

In carrying out the invention as shown a shank 5 is provided, carrying at its lower end 40 a pair of depending box-engaging jaws 6 and 7 and at its upper end a pair of lid-engaging jaws 8 and 9. It will be observed by reference to Fig. 3 that the openings between these pairs of jaws are arranged in substantially 45 parallel planes, so that when the jaws 6 and 7 are placed astride the rear side of the box near the end the jaws 8 and 9 will be in position to embrace the end edge of the cover.

In the preferred construction the entire device 50 is constructed of a single rod or wire, the lower portion of which is bent upon itself, as at 10, whereby the jaw 6 is formed and the

end of said upturned portion being again bent downwardly, so that it will be substantially parallel to, but spaced from, the jaw 6, 55 and will in turn form the jaw 7. These jaws, it will be observed, are offset from the shank 5 by bending said shank at the upper end of the jaws.

The lid-engaging jaws 8 and 9 are formed 60 by coiling the upper end of the shank, the first offset portion forming the jaw 8 and the second corresponding convolution the other jaw, 9, which overlaps the first jaw. The end of the coil is offset to form a projecting operating-finger 12, adapted to be engaged by the lid, as is hereinafter more fully described.

In applying the device the jaws 6 and 7 are placed astride the rear side of the box, contiguous to one end thereof. The jaw 7 will 70 therefore be located directly in the corner, and the looped jaw 6 will bear against the exterior face of the rear side. The edge of the lid is then inserted between the jaws 8 and 9, and this is easily accomplished by first 75 placing the lid against the projecting finger 12 and forcing the jaws apart. By this arrangement it will be seen that the shank is located directly alongside of the cover and will therefore not be in the way.

80 There are several important advantages obtained by this construction. In the first place, because of the relation between the pairs of jaws the lower pair can be placed astride the rear side of the box, and thus positively hold 85 the shank against movement, as distinguished from an engagement with the end wall of the box, in which case the stability would correspond to the degree of the frictional clamping action. In connection with this positive 90 support is employed the lid-clamp, which holds the lid against movement in either direction. Furthermore, the device is not liable to accidental displacement, as there are no 95 projecting portions likely to be struck while moving the box or removing its contents.

From the foregoing it is thought that the construction, operation, and many advantages of the herein-described invention will be apparent to those skilled in the art without further description, and it will be understood that various changes in the size, shape, proportion, and minor details of construction may be resorted to without departing from 100

pirit or sacrificing any of the advantages
e invention.

ving thus described the invention, what
im is--

box-lid holder formed of a single piece
etal and comprising a shank having at
ower end a pair of offset box-engaging
formed by bending the lower portion of
shank upwardly and bending said up-
ed portion at an intermediate point down-
ly, the downwardly-extending extrem-
comprising one jaw and being arranged
gage the interior rear face of the box at
corner and the upwardly-bent portion
shank contiguous thereto comprising the
jaw and engaging the exterior rear face
e box, the shank being bent at the up-
nd of the intermediate bend of the lower

portion, whereby said shank is offset from
the jaws, and will thus be located alongside 20
of the end of the lid when the jaws are in
place upon the box, and a pair of lid-engag-
ing jaws arranged at the upper end of the
shank, said latter jaws comprising a coil ar-
ranged to embrace the end edge of the lid 25
and having its free end offset to form an op-
erating-finger for spreading the sections of
the coil apart.

In testimony that I claim the foregoing as
my own I have hereto affixed my signature in 30
the presence of two witnesses.

WILLIAM GIES, JR.
